UNITED STATES PATENT OFFICE.

ALBERT ROSLINGTON BUCKTON, OF MANCHESTER, ENGLAND, ASSIGNOR TO
HUGH STEVENSON AND SONS, LIMITED, OF MANCHESTER, ENGLAND.

FOLDING OR COLLAPSIBLE BOX OF CARDBOARD OR THE LIKE.

SPECIFICATION forming part of Letters Patent No. 749,125, dated January 5, 1904.

Application filed March 7, 1903. Serial No. 146,711. (No model.)

To all whom it may concern:

Be it known that I, ALBERT ROSLINGTON BUCKTON, fancy-box manufacturer, a subject of the King of Great Britain, residing at Victoria Mills, Pollard street, Manchester, in the county of Lancaster, England, have invented certain new and useful Improvements in Folding or Collapsible Boxes of Cardboard or the Like, of which the following is a specification.

10 My invention relates to an improved manufacture of folding or collapsible boxes made of cardboard or like material.

In the accompanying two sheets of drawings, Figure 1 is a plan of the box with the sides and ends collapsed. Fig. 2 is a plan, and Fig. 3 an end elevation, of the box with the sides and ends raised and showing the extension-pieces outside. Fig. 4 is a similar view to Fig. 3, but showing the extension-pieces turned inside the box and the tongues on the extension-pieces passed through slots in the box ends. Fig. 5 is an end elevation of Fig. 4. Fig. 6 is a perspective view of the complete box and lid.

25 I construct the box of any desired number of pieces of cardboard, with turned-in corners *a* diagonally bent and wired at *b* or otherwise fastened onto the ends *c* of the box. The ends *c* have extension-pieces *d* either integral with the end or a separate piece hinged to it, and these extension-pieces *d* turn inside the box over the turned-in and diagonally-bent corner-pieces when the box is made up. So far this is a known form of box,

30 both the diagonally-bent corner-pieces and extension-pieces being in common use.

35 My improvements consist of a tongue *e*, cut

out of each extension-piece *d* and with a bend or crease to form a hinge along its line of junction with the piece *d* and with its free end pointing toward the junction of the parts *c* and *d*. I also cut a corresponding horizontal slot *f* in each end *c*, through which slots the tongues *e* pass when the box is made up and after the extension-pieces *d* have been 45 turned inside the box. These tongues *e* may either fit underneath the rim of the lid *g* or, preferably, outside the lid-rim, as shown in Fig. 6, which shows a cord *h* attached to each tongue *e* and connected by a hook and eye or equivalent fastening *i* to form a carrier for the box, as well as to hold the tongues closely to the box.

What I claim as my invention, and desire to secure by Letters Patent of the United States, is—

In a folding box having diagonally-bent corner-pieces and extension-pieces hinged to the upper part of its ends, tongues formed out of the extension-pieces and with their 60 free ends pointing toward the junction of the ends of the box and the extension-pieces, of slots formed in the ends and adapted to receive the tongues when the extension-pieces are turned inside the box, said tongues projecting upwardly through the slots substantially as herein set forth.

In witness whereof I have hereunto set my hand in presence of two witnesses.

ALBERT ROSLINGTON BUCKTON.

Witnesses:

WILLIAM BURTON COOPER,
ALBERT JAMES HAMPTON.
